SKIVING MACHINE

Milton H. Roske, Milwaukee, Wis., assignor to
 United Shoe Machinery Corporation, Paterson,
 N. J., a corporation of New Jersey

Application January 9, 1934, Serial No. 705,931
 Renewed May 3, 1935

13 Claims. (Cl. 69—16)

This invention relates to skiving machines and is herein illustrated as embodied in a machine of the well-known Amazeen type for skiving the edges of pieces of upper leather.

5 In the manufacture of certain kinds of shoes, it is desirable to produce on a single part of an upper two or more scarfs which differ in width or in character or in both. For example, it may be necessary to provide along the top and front of a 10 quarter a shoulder or fold scarf, to produce along the bottom a feather edge or underlap scarf and to produce along the back a seam scarf. In such and similar cases, it is desirable that the operator be able instantly to change the operative positions of the work-engaging parts of the machine 15 so as to avoid delay in producing first one kind of scarf and then another. A machine in general use comprises a knife, a roll for feeding the work to the knife, said roll being angularly adjustable to vary the inclination of the scarf produced, a presser for holding the work on the roll and a guide for engaging the edge of the work.

According to one feature of the present invention, a single operator-controlled member may be 25 manipulated to change the angular position of the roll so as to change the inclination of the scarf produced and at the same time to adjust the edge guide so as to change the width of the scarf. In the illustrated construction, the work 30 is fed to a rotary disk knife by a feed roll mounted on an angularly adjustable support on which the presser and edge guide are slidable, a treadle being provided manipulation of which adjusts the feed roll support angularly and simultaneously 35 adjusts the presser and edge guide along the support. The limits of angular movement of the feed roll support are determined by adjustable stops so that, with the treadle raised, a scarf of certain predetermined inclination is produced 40 and with the treadle depressed a scarf of different predetermined inclination is produced. The machine is constructed and arranged to produce a narrow fold or shoulder scarf of a predetermined width when the treadle is raised and a 45 wider feather edge scarf when the treadle is depressed.

It is desirable at times to vary the width of the scarfs thus produced; and according to another 50 feature of the invention, a second operator-controlled member is provided which may be manipulated at any time, irrespective of the adjustment of the other parts to determine the inclination of the scarf, to move the edge guide into a different position.

55 These and other features of the invention, in-

cluding certain details of construction and combinations of parts, will be described as embodied in an illustrated machine and pointed out in the appended claims.

Referring now to the accompanying drawings, 5 Fig. 1 is a front elevation of a machine in which the present invention is embodied.

Fig. 2 is a section on the line II—II of Fig. 1 showing the presser and guide and the manner in which they are mounted, 10

Fig. 3 is a more or less diagrammatic elevation showing the position of the work-engaging parts when the treadle is in raised position, the plane of the cut of the knife being indicated by a line, 15

Fig. 4 is a section of a piece of work showing the kind of scarf which is produced when the parts of the machine are in the positions shown in Fig. 3, 20

Fig. 5 is an elevation after the manner of Fig. 3 showing the work-engaging parts in the position occupied by them after the treadle has been depressed to adjust the feed roll angularly and to adjust the edge guide to the right, and 25

Fig. 6 is a section of a piece of work showing the kind of scarf which is produced when the work-engaging parts of the machine are in the positions shown in Fig. 5, 30

The illustrated machine is similar in many respects to the machine disclosed in United States Letters Patent No. 1,866,918, granted June 12, 35 1932, upon an application filed in the name of Milton H. Ballard. The present machine, like that of the patent, comprises a rotary disk knife 9, a rotary feed roll 11 and a rotary feed disk 13. The knife is manually adjustable substantially 40 vertically toward and from the feed roll. The feed disk presses a portion of the work against a reduced end of the feed roll and aids in feeding the work. The feed roll shaft is rotatable in a block 15 which is adjustable horizontally 45 on a support 17, said support being angularly adjustable in a curved guideway 18 the center of curvature of which lies in a horizontal axis which passes through an element on the upper surface of the feed roll. It will be noted, however, that by adjusting the block 15 to the right or left, the position of this point with respect to the feed roll may be changed. The block 15 carries a superstructure by which the feed disk is carried so that angular adjustment of the feed roll support 17 adjusts the feed disk. The feed disk and feed roll thus preserve at all times their relative positions. The curved guideway in which the feed roll support is adjusted is located 50 at the outer end of a large arm 19, said arm 55

being adjustable in a horizontal path about the axis of a vertical stud 21 to adjust the feed roll toward and from the knife; and the feed roll shaft is connected by a telescoping shaft 23 and a universal joint with a driving pulley 25. The feed roll support 17 is connected by a link 27 with a treadle-controlled arm 29 pivoted at 31 to the base of the machine and carrying a small block 33. Two small adjusting nuts 35 threaded on a small rod 37 limit the rocking movement of the arm 29 and hence the extent of angular adjustment of the feed roll support 17. The arm 29 is connected by a link 30 and a pivot 32 with the upper end of a treadle rod 39 in such manner that vertical movement of the rod swings the arm to the right or left. The lower end of the rod is connected to a treadle 41 normally held in raised position by a spring 40 to hold the feed roll 11 in its up position in which the uppermost element of its periphery is parallel to the plane of the knife or substantially so. An edge guide 43 which is carried indirectly by the block 15 has a stem 53 which carries a yieldingly mounted adjustable presser 46. The machine as thus far described may be substantially the same as the patented machine and will not be described further in detail. It will be noted, however, that the work to be skived is fed away from the observer, as viewed in Fig. 1, with its edge against the guide 43 and its margin beneath the presser, the skived work passing beneath the rotary knife 9. With the parts in their normal positions, as shown in Fig. 1, a shoulder or fold scarf will be produced; and when the treadle is depressed to swing the roll in a counterclockwise direction until the small block 33 encounters the right-end stop 35, a feather edge scarf will be produced, the positions in which the two limiting stops 35 are held thus determining the characteristics of the two scarfs.

The presser and edge guide, except for their mounting for quick adjustment in a path transverse to the line of feed of the work, are or may be substantially like the presser and guide disclosed in United States Letters Patent No. 1,180,222, granted April 18, 1916, on an application filed in the name of Alexander M. Alexander. It will be understood that the presser is so mounted by means of pivots and springs that it holds the margin of the work firmly against the periphery of the feed roll irrespective of its position longitudinally of said roll.

In the present construction the presser and edge guide, instead of being horizontally adjustable by hand longitudinally of the feed roll as they are in the patented machine, are automatically adjusted when the feed roll is adjusted angularly by manipulation of the treadle 41 or, as will presently appear, may be so adjusted at any time by manipulating a second treadle 51. The stem 53 of the guide is slidably mounted in a substantially horizontal guideway formed in the rear side of a bracket 55 which is rigid with the block 15 and is adjusted angularly when the feed roll support is so adjusted, said stem being held in this guideway by a thin plate 57 (Fig. 2) and screws 59. In the normal position of parts, with the treadle 41 raised, the stem 53 is held to the right by a tension spring 61 as far as is permitted by a stop pin 63 on the stem which is held against an inclined face on an adjustable stationary cam 65, this spring being fastened at one end to the stem 53 and at the other to a pin 67 driven into the heavy arm 19. The stationary cam 65 is pivoted at 69 to a narrow plate

71 and may be adjusted into and held in various angular positions about its pivot 69 by a thumb-screw 73 threaded through an ear on the cam 65 and bearing against an ear on the narrow plate 71. The narrow plate 71 is adjustably mounted on a larger plate 75 by means of two screws 77 which pass through substantially vertical slots in the plate 71 and are threaded into the plate 75. The large plate 75 is adjustably mounted on the heavy arm 19 by two screws 79 which pass through a substantially horizontal slot in the plate 75 and are threaded in the arm 19. With this construction, the stationary cam 65 may be adjusted vertically after the screws 77 have been loosened, horizontally after the screws 15 79 have been loosened and angularly about its pivot 69.

In Fig. 3, the presser 46, the edge guide 43 and the feed roll 11 are shown in the positions occupied by them in Fig. 1; and with these parts in these positions, a comparatively narrow fold scarf will be formed in the work, as shown in Fig. 4. If now the treadle 41 is depressed to tilt the feed roll counterclockwise, the tension spring 61 will pull the presser and guide to the right, the stop pin 63 (Fig. 1) riding up the inclined face of the cam 65 so that the parts will occupy the positions shown in Fig. 5 and a comparatively wide feather edge scarf will be produced on the work 100, as shown in Fig. 6. The angular movement of the roll takes place about a point such as the one indicated at x in the upper surface of the feed roll as it does in the machine of the Ballard patent. Thus the operator, by manipulating a single treadle, may instantly change from a narrow fold scarf to a wider feather edge scarf, and vice versa.

It is desirable at times to produce a seam scarf, that is a scarf like the feather edge scarf but of somewhat less width and with an edge which is of appreciable thickness. To form such a scarf, the parts of the machine should be in the positions shown in Fig. 5 but with the presser and guide moved to the left, for example into a position in which the work-engaging face of the guide 43 is in register with the point x. To this end (Figs. 1, 2), the second treadle 51 has a treadle rod 81 normally held up by a spring 83, the upper end of said rod being pivoted at 85 to the horizontal arm of a bell-crank lever 87, said lever being pivoted at 89 to the heavy arm 19 and having an upwardly extending arm which will engage the stop pin 63 and push the stem 53 to the left when said bell-crank lever is rocked counterclockwise by depressing the treadle 51. In order to limit the extent of movement of the presser and guide to the left, a slotted stop plate 91 is adjustably fastened to the bracket 55 by a screw 93. When, therefore, it is desired to produce a seam scarf, both treadles are depressed. It should be noted, however, that the presser and guide may be adjusted along the periphery of the feed roll in any angular position of the feed roll whenever such adjustment may be desired.

Although the invention has been set forth as embodied in a particular machine having a rotary disk knife and an angularly adjustable feed roll, it should be understood that the invention is not limited in the scope of its application to the particular machine which has been shown and described.

Having described my invention, what I claim as new and desire to secure by Letters Patent of the United States is:

1. A skiving machine having, in combination, 75

work-engaging parts including a knife, a feed roll and a presser so constructed and arranged that changing their angular relation changes the angle of the scarf produced, an edge guide adjustable transverse to the direction of feed movement of the work to change the width of the scarf, a single operator-controlled member manipulation of which changes the angular relation of the first-named parts and adjusts the edge guide, and a second operator-controlled member which may be manipulated to adjust the edge guide without changing the angular relation of the other parts.

2. A skiving machine having, in combination, work-engaging parts including a knife, a feed roll and a presser so constructed and arranged that changing the relative angular positions occupied by the knife on the one hand and the feed roll and presser on the other hand changes the angular inclination of the scarf produced, an edge guide adjustable transverse to the direction of feed movement of the work to change the width of the scarf, a single operator-controlled member manipulation of which changes the angular relation between the knife and the presser and roll and adjusts the edge guide, and a second operator-controlled member which may be manipulated to adjust the edge guide irrespective of the relative angular positions of the other parts.

3. A skiving machine having, in combination, a knife, a feed roll, a support for the feed roll, a presser and edge guide, a carrier for the presser and guide mounted for adjustment longitudinally of the feed roll, a single operator-controlled member manipulation of which changes the angular relation between the knife and the feed roll and adjusts the carrier for the presser and edge guide, and a second operator-controlled member manipulation of which adjusts the carrier for the presser and edge guide irrespective of the angular relation between the knife and the feed roll.

4. A skiving machine having, in combination, a knife, a feed roll, a support for the roll angularly adjustable to vary the inclination of the scarf produced, a presser for holding the work against the roll, a guide for engaging the edge of the work, a carrier for said presser and guide slidably mounted upon said feed roll support, and means operated by adjustment of the roll support angularly for sliding the carrier for the presser and edge guide along the feed roll support.

5. A skiving machine having, in combination, a knife, a feed roll, a support for the roll angularly adjustable to vary the inclination of the scarf produced, a presser for holding the work against the roll, a guide for engaging the edge of the work, a carrier for said presser and guide slidably mounted upon said feed roll support, and a single operator-controlled member manipulation of which adjusts the feed roll support angularly and simultaneously adjusts the carrier for the presser and edge guide along the feed roll support.

6. A skiving machine having, in combination, a knife, a feed roll, a support for the roll angularly adjustable to vary the inclination of the scarf produced, a presser for holding the work against the roll, a guide for engaging the edge of the work, a carrier for said presser and guide slidably mounted upon said feed roll support, a single operator-controlled member manipulation

of which adjusts the feed roll support angularly and simultaneously adjusts the carrier for the presser and edge guide along the feed roll support, and a second operator-controlled member which may be manipulated to adjust the carrier only.

7. A skiving machine having, in combination, a knife, a feed roll, a support for the roll angularly adjustable to vary the inclination of the scarf produced, a presser for holding the work against the roll, a guide for engaging the edge of the work, a carrier for said presser and guide slidably mounted on the roll support, and a cam adapted to slide the carrier along the roll support when said roll support is adjusted angularly.

8. A skiving machine having, in combination, a knife, a feed roll, a support for the roll angularly adjustable to vary the inclination of the scarf produced, a presser for holding the work against the roll, a guide for engaging the edge of the work, a carrier for said presser and guide slidably mounted on the roll support, and a cam adapted to slide the carrier along the roll support when said roll support is adjusted angularly, said cam being adjustable to vary the extent to which the carrier is moved.

9. A skiving machine having, in combination, a knife, a feed roll for advancing the work to the knife, a presser for holding the work on the feed roll, an edge guide for engaging the edge of the work, yielding means for normally holding the roll, the presser and the edge guide in positions to cause the knife to produce on the work a narrow fold scarf, and a single member manipulation of which adjusts the roll, presser and guide into positions to cause the knife to produce a wider feather edge scarf.

10. A skiving machine having, in combination, a knife, a feed roll angularly adjustable to vary the inclination of the scarf produced, a guide for engaging the edge of the work, and a cam adapted to adjust the guide longitudinally of the feed roll when said feed roll is adjusted angularly.

11. A skiving machine having, in combination, a knife, a feed roll angularly adjustable to vary the inclination of the scarf produced, a guide for engaging the edge of the work, and a cam adapted to adjust the guide longitudinally of the feed roll when said feed roll is adjusted angularly, said cam being adjustable to vary the extent of the adjustment imparted to the guide.

12. A skiving machine having, in combination, a knife, a feed roll angularly adjustable to vary the inclination of the scarf produced, a guide for engaging the edge of the work, a stem by which the guide is carried, a treadle manipulation of which adjusts the roll angularly, and a stationary cam adapted to engage and move the stem of the guide when the treadle is manipulated.

13. A skiving machine having, in combination, a knife, a feed roll, a support for the feed roll, an arm upon which the support is mounted for angular adjustment, a presser for holding the work against the roll, a guide for engaging the edge of the work, a carrier for said presser and guide slideable on the roll support, and a cam mounted on the arm and adapted to slide the presser and guide on the roll support when said support is adjusted angularly.

MILTON H. ROSKE.
